FRACTIONATION OF LIQUIDS

Earl Biddle Conklin, Detroit, Mich., and Joseph J. Lawton, Syracuse, N. Y., assignors to Semet-Solvay Company, New York, N. Y., a corporation of New York

Application September 25, 1930, Serial No. 484,288

10 Claims. (Cl. 196—73)

This invention relates to a process for fractionating a liquid containing lower and higher boiling compounds into its various constituents in a pure form. More particularly it relates to the fractionation of light oils which are obtained as by-products in the destructive distillation of coal, or coal tar, and the invention includes correlated improvements and discoveries whereby and wherewith the production of pure products from a mixture is accomplished.

An object of the invention is to provide a process for the fractionation of a liquid mixture in accordance with which the various constituents thereof may be readily and efficiently obtained on a commercial scale.

Another object of the invention is to accomplish the separation of a liquid mixture into its various constituents whereby the yield and purity of the separated constituents are improved and the cost of operation lowered.

A further object of the invention is to provide a process which may be substantially continuously and automatically operated and in which the amount of material required for treatment is lessened.

More specifically it is an object of this invention to fractionate a light oil in order to obtain therefrom pure benzol, toluol and xylols and in which the toluol and xylols are obtained in a single distillation step. The term "pure", it will be understood, covers products which conform satisfactorily to the specifications of purity as set up by the usual trade channels into which the products go, thus pure benzol does not mean chemically pure benzol, but a benzol of a quality which satisfactorily meets the requirements of benzol users.

Other objects of the invention will in part be obvious and will in part appear hereinafter.

The invention accordingly comprises the several steps and the relation of one or more of such steps with respect to each of the others thereof, which will be exemplified in the process herein-after disclosed, and the scope of the invention will be indicated in the claims.

In the practice of the invention a liquid containing lower and higher boiling constituents such as a light oil may be distilled to separate the lower boiling constituents as a single condensate from the higher boiling constituents as a residue. The condensate may then be treated chemically in order to remove undesirable materials therefrom which in the case of a light oil may be unsaturated hydrocarbons, resins, tar-like materials, etc., and the treated condensate distilled

to separate the lower boiling compounds, as a distillate containing all the distilled vapors and a residue containing the higher boiling constituents. The condensate thus obtained may then be introduced into a column at an intermediate point thereof and subjected to the action of heated vapors of the higher boiling constituents, thus effecting removal of the lowest boiling members as a distillate and obtaining as a liquid residue the higher boiling compounds free from the lowest boiling compounds. A liquid residue may be withdrawn into a collecting vessel capable of supplying another column, even though the flow of liquid residue into the vessel or accumulator may be temporarily discontinued, due to an improper temperature gradient within the column, thus allowing a part of the lowest boiling compounds to be present in the liquid residue. When such a condition arises the flow of liquid residue into the vessel is discontinued and the temperature gradient readjusted in order to again give a residue which shall be free from the lowest boiling constituents. In the meantime the other column is fed continuously from the liquid accumulated in the vessel. The liquid free from the lowest boiling compounds may be introduced into another column at a point intermediate thereof and subjected to the distilling effect of rising heated vapors of the higher boiling compounds, thus effecting removal of the lowest boiling compound which is condensed and obtaining a liquid residue composed of the higher boiling constituents and free from the lowest boiling constituent. This residue is collected in a vessel and fed to a succeeding column in a manner like unto that hereinbefore described and the operation may be repeated the number of times necessary to effect the separation of the liquid into a desired number of constituents. If such a successive distillation process each succeeding still is normally operated at a reduced feed and in proportion to the amount of product removed in the preceding column. As hereinbefore indicated, these various operations may be carried out as a continuous process.

The practice of the process of this invention will be exemplified by its application to the fractionation of a light oil. The light oils are those mixtures which are obtained as a by-product in the destructive distillation of coal or by the distillation of coal tar. The light oils are a mixture of higher and lower boiling compounds largely belonging to the aromatic series of organic compounds and containing chiefly benzol, toluol, and xylols with smaller amounts of compounds hav-

ing boiling points lower than benzol and of compounds having boiling points higher than the xylols.

We have found that the principal constituents 5 of light oil, namely benzol, toluol and the xylols may be obtained in pure form by first distilling the light oil to effect a separation between the lower boiling compounds containing the desired constituents and the higher boiling materials 10 such as resins, tar-like substances, naphthalene, etc. in which all of the distillate is produced as a single condensate, washing the condensate with acid, and subjecting the washed condensate to a further distillation whereby the benzol, toluol, 15 etc. are obtained as a single water-white distillate and the higher boiling compounds remain as a residue. The distillate is then separated into a product containing compounds having boiling points lower than that of benzol, pure benzol, pure 20 toluol and xylols by a succession of distillations in which the mixture fed to the columns is free from the lower boiling constituent secured as a condensate in the preceding column and in which the pure toluol and the xylol fractions are withdrawn from a single column. 25

Thus, when conducting the process for the fractionation of light oil into "first running", benzol, toluol, xylols and higher molecular compounds, and a residue containing the compounds 30 having boiling points higher than xylols, the light oil may be first subjected to a continuous distillation with direct steam to effect a separation of the lower boiling constituents into a condensate containing all of the distilled vapors 35 and a tarry residue containing the higher boiling constituents. This condensate may then be treated with sulfuric acid to remove impurities such as unsaturated hydrocarbons, which treatment may be followed with an alkali wash in 40 order to remove the acid and the treated condensate introduced into a column and again subjected preferably in a continuous manner to the action of direct steam, whereby the lower boiling constituents, i. e., those which it is desired to recover 45 in pure form, are separated as a single distillate from the higher boiling constituents as a residue.

The distillate, which should be water-white, is then introduced into a column at an intermediate point and vapors of the higher boiling constituents admitted to the base of the column wherein 50 they rise in contact with the descending distillate and remove therefrom the compounds having boiling points lower than that of benzol. In this distillation it may be desirable to permit a portion 55 of the benzol to pass over into the distillate with the lower boiling compounds in order to insure complete removal of the lower boiling compounds. It may also be desirable at this point to permit a larger amount of the benzol to pass into 60 the distillate than is actually required to insure freedom from lower boiling constituents, this being governed by the market conditions at the time, and thus prepare a product which would be suitable for use as a motor fuel in the manner in 65 which benzol is usually so utilized.

The liquid residue from the column, and which is commercially free from compounds having boiling points lower than benzol may be collected in a vessel or accumulator which is capable of 70 serving as the source of supply for another column in which pure benzol is separated, so that if it is necessary to discontinue collection of the residue from the first column due to contamination thereof with lower boiling constituents, this may be 75 effected without discontinuing the feed to the

succeeding column. The liquid free from compounds having boiling points lower than benzol is then admitted to a column in which it is contacted with vapors of toluol and higher boiling compounds under conditions such that all of the benzol is removed and a liquid residue obtained which is free therefrom. This liquid residue is collected in a vessel capable of supplying a succeeding column into which it is introduced at an intermediate point and therein distilled by contact with heated vapors of the higher boiling constituents which may be admitted thereto at the base. From this column toluol may be withdrawn at the top as a distillate of pure toluol, the highest boiling compounds withdrawn from the base as a residue and a fraction containing compounds having boiling points between that of toluol and the highest boiling constituents withdrawn from a point intermediate that at which the benzol-free liquid is introduced and that at which the vapors are admitted to the column. The fraction withdrawn at an intermediate point is xylol which frequently has a boiling range of 10° C. and meets commercial specifications for "10" xylol without further treatment. The distillation is continued until the acid wash color number, preferably is not in excess of 12, Barrett Colorimetric Scale. 100

If desired the residue from the still in which the pure toluol is separated, and which may contain an amount of xylols, may be introduced into a still and heated therein as by means of indirect steam, and the vapors passing off led into a column in which the xylols are separated from the higher boiling compounds. The quality of the 110 xylol obtained by this distillation will depend upon the character of the distillation and the type of column into which the vapors are led. Thus, if the still is a comparatively small one the xylol fraction will have a final boiling range which 115 may vary considerably, but if the vapors are led into a larger column, a greater amount of rectification may be accomplished, and the xylol refined to a point at which the final boiling range will not vary from specifications by more than 120 1° to 10° C.

The foregoing procedure for the fractionation of light oil may be carried out more advantageously if operated in a continuous manner. When so operating the crude light oil, condensates and various liquid residues, free from lower boiling constituents, are continuously, successively and substantially automatically fed through a system consisting of a plurality of reservoirs, feeding means, columns and accompanying apparatus. 125

The invention will now be more particularly described with reference to the accompanying drawings which illustrate diagrammatically a procedure and an arrangement of apparatus in 135 which pure benzol, pure toluol and pure xylols may be obtained from a crude light oil. It will be understood that this described an illustrative embodiment of a manner in accordance with which the invention may be practiced and that 140 the invention is not limited thereto.

Crude light oil from a storage tank 1 is fed by means of a pump 2 through a constant-level reservoir 3 and a U-trapped conduit 4 into a column 5 at an intermediate point. In this column the crude light oil is subjected to distillation, preferably by means of direct steam admitted by a pipe 90 at the base of the column, whereby the crude oil is separated into a condensate of the lower boiling compounds and con- 150

taining all of the distilled vapors and into a residue containing the higher boiling compounds such as resins, tarry materials, naphthalene, etc. The vapors passing from the column are conducted through a condenser 7 into a separator 8 in which the water and oil are separated, and the oil passes to a storage vessel 9. By means of a pump 10 the distilled light oil is passed to a washer 11 in which it is chemically treated with sulfuric acid introduced through pipe 12. The resulting acid sludge is permitted to settle and may then be withdrawn from the washer into a tank 91.

After the washing treatment with sulfuric acid, the oil is then neutralized with an alkali introduced through pipe 13.

The washed and neutralized condensate, preferably without separation of the aqueous neutralization liquor, is passed through a pipe 14 to a storage holder 15, from whence, by means of a pump 16, a constant-level reservoir 17 and a U-trapped conduit 18, it is fed into a column 19 at an intermediate point, and distilled therein, preferably with direct steam through a pipe 23, to obtain a distillate containing all of the evolved vapors and the constituents which it is desired to recover in pure form, and a residue of the resins, sulfate, naphthalene, etc. The residue is led from the base of the column through a U-shaped pipe 92 to a cooling coil 24, which may be of the worm type, and then through a U-shaped pipe 93 in which the U is in the reverse direction from that in the pipe 92 to a collecting tank 25. The vapors from the still pass through a condenser 20 into a separator 21 in which the water and oil separate and the oil is then led to a storage tank 22. The distillate in the storage tank 22 contains those constituents of the light oil other than the highest boiling constituents of a tarry or resinous nature, naphthalene, etc. and is primarily a mixture of benzol, toluol and xylos with a small amount of compounds which have a boiling point lower than that of benzol.

The alkali used for neutralizing the washed oil in washer 11, as described above, may be caustic soda, ammonia, or other suitable neutralizing agent. As disclosed in U. S. Patent 1,779,944 of October 28, 1930, to Joseph J. Lawton, the alkali used is preferably ammonia which has been found to result in improvements in operation as described in said patent of Lawton. The use of ammonia, while possessing certain important advantages over caustic soda as heretofore employed, has been found to result in operating difficulties due to the formation of emulsions in the washed oil which prevented an efficient separation of the aqueous neutralizing solution from the oil being treated. As brought out in the Lawton patent, it has been found that these emulsions are broken down, and the use of ammonia as the neutralizing agent with attendant advantages, is made possible by subjecting the neutralized oil containing a portion or all of the aqueous neutralization liquor, which may be somewhat alkaline with ammonia, to subsequent distillation with direct steam, as conducted in column 19 described above in connection with the present invention. It has further been found in accordance with the present invention that the formation of emulsions is inhibited to a surprising extent and the difficulty of breaking up emulsions, if formed, is materially reduced, by subjecting the crude light oil to a preliminary distillation with direct steam as conducted in distilling column 5, described above.

The sequence of operations comprising (1) first subjecting the crude light oil to a preliminary distillation with direct steam, (2) washing the distillate with sulfuric acid, (3) neutralizing the washed oil with ammonia, and (4) then distilling the neutralized oil with direct steam, preferably in the presence of a portion or all of the neutralization liquor, has been found to yield a product of exceptional purity and freedom from sulfur compounds, resins and other impurities and to result in lowered operating costs and increased yield of product.

The mixture of benzol, toluol, etc., produced as above described, is introduced into a column 29 at an intermediate point by means of a pump 26, a constant-level reservoir 27 and a U-trapped conduit 28. In this column the compounds having a boiling point lower than that of benzol are removed by contacting with heated ascending vapors of higher boiling constituents which are admitted at the base of the column through a pipe 33 from a still or vaporizer 35. The still or vaporizer 35 has previously been charged with a liquid composed of benzol and higher boiling compounds, but commercially free from compounds having boiling points lower than that of benzol. It is desired to mention here that the liquid composed of benzol and high boiling compounds may be obtained at the start of the process by a temporary intermittent operation until a sufficient depth of liquid is reached in the vaporizer which is free from compounds having a boiling point lower than that of benzol. This same general method of obtaining a liquid of a suitable composition in each succeeding vaporizer is used at the start. The operation of the column is such that the lower boiling compounds pass from the top and are accompanied by a portion of the benzol which assures removal of the lower boiling compounds and reduces the volatility of the liquid produced. By means of a condenser 30 the distilled vapors are condensed and pass into a separator 31 from which the oil usually designated as "first runnings", and composed preponderantly of compounds having a lower boiling point than benzol, is withdrawn and conducted to a receiver 32.

The liquid in the base of the column which, under proper operation, will be free from the lower boiling compounds, is conducted to the vaporizer 35 by means of a U-trapped pipe 34. From the vaporizer it is conducted by means of a valved pipe 36 to a storage tank 37 in which it is held until utilized in the next succeeding column for recovery of pure benzol. The operation of the column, as above indicated, is conducted so that the liquid flowing from the base of the column to the vaporizer will be free from the lower boiling constituents and accordingly the liquid flowing from the vaporizer to the storage tank will be free from such compounds. It will be noted also that provision is made for discontinuing the flow of liquid from the vaporizer to the storage tank, and this provision is made and the storage tank is of such a capacity as to be able to continuously supply the next succeeding column even though the flow of liquid from the vaporizer to the storage tank may be temporarily discontinued in the event that a change in the temperature gradient in the column is of sufficient magnitude as to permit a part of the low boiling constituents to pass into the vaporizer. When this condition arises the valve in the pipe 36 is closed and no liquid is permitted to pass into the storage tank until the temperature gradient

in the column has been readjusted and low boiling constituents are no longer passing to the vaporizer. Thus the succeeding column is always fed with a liquid which does not contain 5 any constituent having a boiling point lower than that constituent which it is desired to recover in the pure form in that column.

The liquid in the storage tank 37 which is free 10 from compounds boiling lower than benzol is passed to the column 41 by means of a pump 38, a constant-level reservoir 39 and a U-trapped conduit 40 and is therein distilled by means of vapors of higher boiling constituents admitted at the base of the column through a pipe 44 and 15 arising in a vaporizer 46. The vaporizer is charged at the outset of the operation with a liquid which is free from benzol. The benzol evolved passes from the top of the column through a condenser 42 into a receiver 43, from which 20 it may be conducted to storage, or to drums, or utilized in any desired manner. The operation of this column and of the succeeding toluol and xylol columns is so carried out that the liquid in the uppermost pan or pans of the column is 25 composed wholly of that constituent which is being distilled over in order that a sharp cut may be made between this constituent and the higher boiling compounds. The benzol-free liquid is withdrawn from the bottom of the column through a U-trapped pipe 45 and passes to the 30 vaporizer, from whence, by means of the valved pipe 47 it flows to a storage tank 48. The provision of the valved pipe 47 in this instance is for the same purpose as that in connection with the 35 "first runnings" column, and thereby the flow to the storage tank may be interrupted in the event that benzol may be found in the liquid flowing from the base of the column. The valve will remain closed until conditions in the column have 40 been readjusted and the liquid in the reservoir is free from benzol, the storage tank being capable of continuously feeding the benzol-free liquid to the next column during the interruption.

The column 52 in which pure toluol is separated 45 is fed with the benzol-free liquid from the storage tank 48 by means of a pump 49, a constant-level reservoir 50 and a U-trapped conduit 51. Distillation is effected by vapors of higher boiling constituents evolved in a still or vaporizer 50 and admitted at the base of the column 60 through a pipe 58. The vaporizer 60 is charged with toluol-free liquid prior to initiating operation of the column. The toluol is withdrawn from the top of the column and passes through the condenser 53 to reservoir 54. A residue 55 containing the highest boiling constituents, as naphthalene, etc., is withdrawn from the base of the column through a U-trapped pipe 59 and conducted to the vaporizer 60. A third product or fraction is withdrawn from the toluol column at 60 a point intermediate that at which the benzol-free liquid is introduced and that at which the vapors of the higher boiling compounds are admitted to the column, preferably at a point which is adjacent to that at which the vapors are admitted. The withdrawal of this fraction, which is composed of compounds having a boiling point between that of toluol and the highest boiling compounds in the distillate being fed to the column (more particularly of xylols which are free from high boiling tarry compounds) and which preferably has an acid wash color which is not in excess of number 12, may be accomplished by a pipe 55 by means of which it is led through a condenser 56 and from thence it passes to a re-

ceiver 57. The constant-level reservoirs 3, 17, 27, 39 and 50 are provided with overflow pipes 94, 95, 96, 97 and 98 respectively by means of which the excess liquid may be returned to the storage tank from which it was pumped.

The products obtained in the various receivers, 80 namely the "first runnings", benzol, toluol and the xylols, are of sufficient purity not to require further treatment prior to entry into the usual commercial channels. The "first runnings product" is a highly volatile product and, as previously indicated, may be modified by permitting a larger or smaller amount of benzol to pass over into this distillate, and if a considerable amount of benzol is so permitted to pass over, it may find use in 85 the preparation of a motor fuel.

Distillation in the column to obtain pure toluol and xylols may be continued until the vapors of the higher boiling constituents in the vaporizer 60 are evolved only with difficulty and until the acid wash color of the xylol fraction is not in excess of 12, Barrett Colorimetric Scale. When it is no longer possible to conduct the distillation so that the acid wash color of the xylol fraction is lower than about 12, the liquid in the vaporizer 60 is allowed to pass to a storage tank 61. This liquid is a toluol-free oil containing a certain amount of solvent naphtha xylols. In order to reduce the xylol content and obtain an added amount thereof, the toluol-free oil is conducted from the tank 61 by means of a pump 62 and pipes 63 and 65 to a storage reservoir 66. From the storage reservoir it flows by a pipe 67 to a washer 68 in which it is treated with sulfuric acid as hereinbefore described with respect to the crude oil condensate first obtained. If desired the toluol-free oil may be conducted directly to the washer by means of a pipe 64, thus by-passing the storage vessel 66. The oil flows from the washer to a vaporizer 70 through a pipe 69, wherein it is heated by means of steam coils, and the vapors conducted through pipes 71 and 73 to a column 75 from which a xylol fraction of ordinary commercial purity passes through a pipe 76 to a condenser 77 and thence to a separator 78 in which any water may be separated out, and the oil conducted to a receiver 79. In the production of this xylol of ordinary commercial purity, a product, suitable for certain purposes, may be obtained in the later stages of the toluol-free oil distillation by eliminating the use of the column 75 and permitting the vapors to by-pass this column through a pipe 74 whereby they are led directly to the condenser and receiver.

If it is desired to prepare a xylol from the toluol-free oil of a degree of purity such that the final boiling range will not vary from the specifications, more than from 1° to 10° C., the vapors may be passed to a column 81 in which a higher degree of rectification is accomplished. The vapors which pass from the column are led through a condenser 82 into a distillate dividing fitting 83 in which the distillate is divided and a portion refluxed by means of a reflux seal 85 to the top of the column, and another portion conducted to 140 a receiver 84. The higher boiling liquids in the xylol columns 75 and 81 are led back to the vaporizer by means of pipes 80 and 86, respectively.

Further, if a xylol having other characteristics 145 is desired, the washer 68 may be by-passed as well as the storage vessel 66, and the toluol-free oil introduced directly to the vaporizer 70, through the pipe 99, after which it may be distilled either through column 75 or column 81, depending upon the properties desired in the finished product.

The columns used for the production of "first runnings", pure benzol, etc., may be constructed in the usual manner with plates or pans suitably fitted with bell-caps, troughs or other effective means for causing intimate contact between the rising vapors and the descending liquid, and the tops of these columns may be provided with cooling coils or dephlegmators. The height of the columns will be governed by the separation which it is desired to bring about in a given column, and it should be such that under normal operating conditions the down-flowing stream of liquid is exposed to the upwardly rising hot vapors for a period of time sufficient to cause the complete vaporization of the constituent of lowest boiling point and removal thereof from the top of the column without admixture with the next higher boiling constituent, and such that the liquid withdrawn from the base of the column shall be wholly free from the lowest boiling constituent.

Thus, in accordance with the process hereinbefore described, the separation of crude light oil into a water-white preliminary condensate by distillation, chemical treatment and repeated distillation, and the resolution of the condensate into a "first runnings" product, benzol, toluol and xylols, may be effected commercially in a satisfactory and efficacious manner. Further, the preliminary distillation and succeeding resolution may be accomplished in a continuous manner. The products obtained are in a condition of purity such that further steps for purification are not required. Further, by the treatment of light oil in accordance with this invention, and in which direct steam is used in the preliminary distillations, products are obtained which have only the characteristic odor of the hydrocarbons and are free from undesirable odors, inasmuch as carrying out the distillation in this particular manner the breaking down of higher boiling sulfur compounds is eliminated. Also, the products are non-corrosive to copper, and the preliminary distillation effects economies, since the high boiling compounds are removed at the outset, thus making it unnecessary to carry them along into succeeding columns, and the amounts of acid and steam required are considerably reduced.

Since certain changes may be made in carrying out the above process without departing from the scope of the invention, it is intended that all matter contained in the above description shall be interpreted as illustrative and not in a limiting sense.

We claim:

1. A process for fractionating light oil which comprises subjecting crude light oil to distillation with steam, condensing the vapors to form a single distillate, treating the condensate with acid, introducing the treated condensate into a column at an intermediate point, distilling with steam, condensing the distillate as a single product, and then successively separating the condensate into its various constituents by introducing the condensate into a column at an intermediate point, producing a condensate composed preponderately of compounds having a lower boiling point than benzol and withdrawing from the column a product free from compounds having a boiling point lower than that of benzol, introducing this product into another column at an intermediate point and distilling benzol therefrom by contact with vapors of the higher boiling compounds, so that all of the benzol is removed, yielding a debenzolized product which is introduced into a further column at an inter-

mediate point and subjected to distillation there-
in in such a manner that pure toluol is withdrawn from the top of the column, a product composed of the highest boiling constituents and having an acid wash color number of at least 12 80 from the bottom of the column, and a fraction containing compounds having boiling points intermediate that of toluol and the highest boiling constituents from an intermediate point.

2. In a process for fractionating light oil, the improvement which comprises separating toluol from higher boiling compounds by introducing a liquid mixture containing toluol and higher boiling compounds and substantially free from lower boiling compounds into a column, subjecting said mixture to the action of heated vapors to distill the toluol, and withdrawing a fraction containing compounds having a higher boiling point than toluol at a point intermediate that at which the mixture to be distilled is introduced 85 and the bottom of said column.

3. In a process for fractionating light oil, the improvement which comprises separating toluol from higher boiling compounds by introducing a liquid mixture containing toluol and higher 100 boiling compounds and substantially free from lower boiling compounds into a column at an intermediate point, subjecting said mixture to the action of heated vapors of the higher boiling compounds to distill the toluol, condensing 105 the distilled toluol, and withdrawing a fraction containing compounds having a boiling point intermediate that of toluene and the highest boiling compounds at a point intermediate that at which the mixture to be distilled is introduced 110 and the bottom of said column.

4. In a process for fractionating light oil, the improvement which comprises separating toluol from higher boiling compounds by introducing a liquid mixture containing toluol and higher 115 boiling compounds and substantially free from lower boiling compounds into a column at a point at which the composition of the liquid in the column is substantially the same as the mixture being introduced, admitting heated vapors of 120 the higher boiling constituents at the base of the column to distill toluol, condensing the distilled toluol, and withdrawing a fraction containing xylols at a point intermediate that at which the mixture to be distilled is introduced and the 125 point of admission of the heated vapors.

5. In a process for fractionating light oil, the improvement which comprises separating toluol from higher boiling compounds by introducing a liquid mixture containing toluol and higher 130 boiling compounds and substantially free from lower boiling compounds into a column at a point at which the composition of the liquid in the column is substantially the same as the mixture being introduced, admitting heated vapors 135 of the higher boiling constituents at the base of the column to distill toluol, condensing the distilled toluol, and withdrawing a fraction containing xylols and having an acid wash color number not in excess of 12 at a point adjacent 140 that at which the heated vapors are admitted.

6. In a process for fractionating light oil, the improvement which comprises separating toluol from higher boiling compounds by introducing a liquid mixture containing toluol and higher 145 boiling compounds and substantially free from lower boiling compounds into a column, admitting heated vapors of the higher boiling compounds at the base of the column to distill the toluol, withdrawing a fraction containing com- 150

pounds having a boiling range intermediate that of toluene and the highest boiling compounds at a point intermediate that at which the mixture to be distilled is introduced and the point of admission of the heated vapors, and continuing the distillation until the withdrawn fraction has an acid wash color number of about 12.

7. In a process for fractionating light oil, the improvement which comprises separating toluol 10 from higher boiling compounds by introducing a liquid mixture containing toluol and higher boiling compounds into a column at an intermediate point, said mixture being substantially free from compounds boiling below toluol, heating a 15 mixture of the higher boiling hydrocarbons in a vaporizer outside the column and admitting heated vapors therefrom at the base of the column to distill toluol, condensing the distilled toluol, withdrawing a fraction containing xylols 20 and having an acid wash color number not in excess of 12 at a point adjacent that at which the heated vapors are admitted, and subjecting the high boiling residue withdrawn from the base of the still to distillation and rectification, 25 whereby xylols are obtained having a final boiling point within a range of 1° to 10° C.

8. A process for the continuous fractionation of light oil which comprises distilling said light oil with direct steam to separate the lower boiling compounds as a single distillate and the higher boiling compounds as a residue, treating said condensate with acid, distilling the treated condensate with direct steam to separate the lower boiling compounds as a single distillate and the higher boiling compounds as a residue, introducing the distillate so produced into a column at an intermediate point and subjecting to the action of vapors of the higher boiling constituents to remove as a condensate all of the compounds having a boiling point lower than benzol, withdrawing the residue free from compounds having boiling points lower than benzol into a collecting vessel capable of supplying another column even though flow of residue into the vessel may be temporarily discontinued, discontinuing the withdrawal of the residue from the column when said residue contains compounds having a boiling point lower than benzol and readjusting the conditions in the column to again give a residue free from the lower boiling compounds, and then admitting the residue to the collecting vessel, introducing the liquid free from lower boiling compounds into another column at an intermediate point, removing the benzol therefrom by subjecting the liquid to the action of heated vapors of toluol and the higher boiling constituents, withdrawing the benzol-free liquid into a collecting vessel capable of supplying another column, as hereinbefore described, feeding the benzol-free liquid into a column at an intermediate point, admitting vapors of the higher boiling compounds at the base of the column whereby the admitted liquid is subjected to the distilling action of such vapors, removing and recovering toluol from the top of the column, withdrawing a residue containing the highest boiling compounds from the base of the column, and withdrawing a fraction containing compounds having boiling points between that of toluol and the highest boiling compounds at a point intermediate that at which the liquid is introduced into the column and the point of admission of the heated vapors.

45 9. A process for the continuous fractionation of light oil which comprises distilling said light oil with direct steam to separate the lower boiling compounds as a single distillate and the higher boiling compounds as a residue, treating said condensate with acid, distilling the treated condensate with direct steam to separate the lower boiling compounds as a single distillate and the higher boiling compounds as a residue, introducing the distillate so produced into a column at an intermediate point and subjecting to the action of vapors of the higher boiling constituents to remove as a condensate all of the compounds having a boiling point lower than benzol, withdrawing the residue free from compounds having boiling points lower than benzol into a collecting vessel capable of supplying another column even though flow of residue into the vessel may be temporarily discontinued, discontinuing the withdrawal of the residue from the column when said residue contains compounds having a boiling point lower than benzol and readjusting the conditions in the column to again give a residue free from the lower boiling compounds, and then admitting the residue to the collecting vessel, introducing the liquid free from lower boiling compounds into another column at an intermediate point, removing the benzol therefrom by subjecting the liquid to the action of heated vapors of toluol and the higher boiling constituents, withdrawing the benzol-free liquid from the column into a vessel and continuing the process for the separation of toluol and higher boiling constituents in the manner hereinbefore set forth for benzol.

10 10. In a process for fractionating light oil, the improvement which comprises separating from said light oil the constituents having lower boiling points than toluol and a mixture containing toluol and higher boiling compounds, passing said mixture in contact with heated vapors to volatilize therefrom toluol and compounds having a boiling point intermediate that of toluol and the highest boiling compounds of said mixture, and separately and simultaneously condensing the volatilized toluol and said compounds of intermediate boiling point to thereby recover from the aforesaid mixture toluol, a residue of the highest boiling compounds and a fraction containing said compounds of intermediate boiling point.
